Filed June 17, 1969, Ser. No. 17,740

Term of patent 14 years

Int. Cl. D9—99
U.S. Cl. D9—224

The side opposite that seen in FIG. 1 is a mirror image of the side shown.

The drawing is shaded to show contrast of color.

I claim:

The ornamental design for a display box, as shown and described.
